UNITED STATES PATENT OFFICE.

HERMANN SCHULZE-BERGE, OF ROCHESTER, PENNSYLVANIA.

MECHANICAL MOVEMENT.

SPECIFICATION forming part of Letters Patent No. 320,706, dated June 23, 1885.

Application filed February 6, 1885. (No model.)

To all whom it may concern:

Be it known that I, HERMANN SCHULZE-BERGE, of Rochester, in the county of Beaver and State of Pennsylvania, have invented a new and useful Improvement in Mechanical Movements, and I do hereby declare the following to be a full, clear, and exact description thereof.

My invention relates to an improvement in eccentrics; and it consists in a combination of mechanical devices by which a slide mounted upon a revoluble shaft or axle, and capable of transmitting an eccentric motion therefrom, can be caused to move adjustably, even while the shaft is in revolution.

My improvement is illustrated in the accompanying drawings, in which Figure 1 is a plan view of the adjustable eccentric. Fig. 2 is a vertical section on the line $x-x$ of Fig. 1. Fig. 3 is an edge view. Fig. 4 is a rear view, partly in section, on the line $x'-x'$ of Fig. 3. Fig. 5 is a front view of a modification. Fig. 6 is a side view of the same, partly in section. Fig. 7 is a view similar to Fig. 6 when the parts have assumed different relative positions.

Like letters of reference indicate like parts.

In the drawings, a represents the rotary shaft or axle of a machine. A portion of its periphery is squared or provided with a rigid block, e , on which is mounted a radially-slotted slide or disk b . (See Figs. 1 and 2.) On this block e the slide is movable in its slot at right angles to the shaft.

Pivotedly attached to the slide b at a point, e , is a pair of levers, d . A second pair of levers, f , is also pivotedly attached to the squared portion of the shaft a , as at g . The levers d and f connect pivotedly at h , from which point a third pair of levers, i , reaches to a sleeve, k , which is movably mounted on the axle a . The pair of levers i connect pivotedly with the sleeve k at points l and l' , which are situate on the sleeve opposite each other. From this construction it becomes evident that if sleeve k be forced toward the disk b that the angle formed by the levers d and f must increase, and that the slide b is forced to move away from its prior location. If the center of the sliding disk b be coincident with the center of the axle a , as shown in Figs. 1, 2, 3, and 4, it becomes evident that the spreading of the levers d and f will cause the disk b to assume the

functions of an eccentric, and that as the angle between the levers d and f approaches one hundred and eighty degrees the eccentricity of the disk will grow correspondingly. The purpose of having double levers d , f , and i is to give steadiness of motion. If convenient, only one of each need be used. The sleeve k is mounted upon the shaft a so as to be movable thereon lengthwise, but is prevented from independent rotation by means of a feather, which fits within a longitudinal and superficial keyway, m , on the shaft. The surface of the sleeve k is grooved, as shown in Fig. 2, in which groove an annular collar, n , is fitted loosely, so that the sleeve can revolve with the shaft a , while the collar or ring n does not partake in the revolving motion. To this end the ring or collar n is provided at two opposite places with studs or pivots o , as shown in Figs. 2 and 4, which studs o are pivoted to the sides of a yoke or lever, p . The yoke p is provided on one end with a lever-handle, p' , (see Figs. 3 and 4,) while the other end of the yoke connects pivotally with any firm or rigid point. In the case illustrated in Figs. 2, 3, and 4 it is pivoted to a part of the frame or bearing q of the shaft a by a pivot, r . If, now, the handle p' of the yoke p be moved around the pivot r , the sleeve k is forced to move along the shaft a , and to spread the toggle-levers d and f , as before described. By these means the slide or disk b is capable of being made to change into an eccentric of adjustable throw at any time, whether the axle a be in motion or not. The distance of motion of the handle p' will determine the eccentricity of the slide or disk b , and by fixing the handle in any desired position the eccentricity may be made permanent.

I have illustrated a device for this purpose in Figs. 6 and 7, which will be explained hereinafter.

The eccentric throw of the disk b when it is properly adjusted and is rotated by the shaft a is communicated to the parts of a machine in any suitable manner.

In the first four figures of the drawings I have shown an annular cam-yoke, S , which is fitted loosely around the disk b , and is provided with a rigid arm, S' . An eccentric rotation of the disk b will communicate a reciprocating and an oscillating motion to the arm S' , as will be readily intelligible.

In place of the knee-lever arrangement shown for eccentrically adjusting the disk *b* upon its shaft, it is obvious that other well-known mechanical devices, such as are used 5 in friction-clutches, can be employed.

The modification shown in Figs. 5, 6, and 7 differs from that before described only in the difference in manner of transmitting motion from the adjustable slide *b*. In these figures 10 the slide *b* is shown movably mounted in a radial slot, *c'*, in a crank-arm, *c*, which is affixed to the end of the rotary shaft *a*. The levers *d* are pivoted to the slide *b*, and the levers *f* to the arm *c* at *g*. The adjustable slide 15 is moved in its slot to a greater or less distance from the axis of the shaft *a* by means of the sliding collar *k* and the mechanism already described. Motion is transmitted from the eccentric by means of a crank-pin, *b'*, or 20 other suitable device. The preferable means for adjusting and fixing the eccentricity of the slide *b* is shown in Figs. 5, 6, and 7. The yoke *p* being pivoted at *r* to the frame *q*, which forms a bearing for the shaft *a*, is pivotally 25 connected at its lower end, *p'*, to a threaded nut, *u*. Into this nut *u* gears a screw, *v*, which is ball-jointed to the frame *q*, as shown at *w* in Fig. 6, and is operated by a hand-wheel, *x*. By turning the wheel *x* the shaft is rotated, 30 and the nut *u* thereby screwed toward and away from its end, thus moving the sleeve *k* and regulating the throw of the eccentric. In this way the eccentricity can be fixed with great accuracy.

35 My improvement is adapted to use in a large number of machines, such as sewing-machines and others. It is especially useful when the throw of the eccentric is to be changed, when the machine is running at a high rate of speed 40 without slackening or stopping the engine. This may be done manually by means of the lever or yoke *p*, or automatically by actuating the yoke from a part of the machine so as to change the throw at determined periods.

45 In applying this adjustable eccentric to regulating the steam-inlet for steam-engines, &c., the handle of the yoke *p* may be set in connection with a governor so as to cause the governor to adjust and regulate automatically 50 the larger or smaller degree of eccentricity of the disks.

What I claim as my invention, and desire to secure by Letters Patent, is—

1. As an adjustable eccentric, a slide connected with a rotary shaft and movable toward and away from the axis thereof, in combination with a non-rotatory yoke or lever capable of moving the slide during rotation of the shaft, said slide being capable of transmitting motion, substantially as and for the purposes described.

2. As an adjustable eccentric, the combination, with a rotary shaft, of a slide capable of

rotating therewith, and movable toward and away from its axis, and provided with a circular surface for transmitting motion, lever-arms connecting with said slide and with said shaft, and capable of imparting the said motion to the slide, and a non-rotatory yoke for actuating the said levers, substantially as and 70 for the purposes described.

3. As an adjustable eccentric, the combination, with a rotatory shaft, of a slide capable of rotation therewith and movable toward and away from its axis, and provided with a circular surface for transmitting motion, a lever-arm connecting with said slide and capable of imparting said motion thereto, substantially as and for the purposes described.

4. As an adjustable eccentric, the combination, with a rotatory shaft, of a slide capable of rotation therewith and movable toward and away from its axis, and provided with a circular surface for transmitting motion, lever-arms connecting with said slide and with said shaft and capable of imparting the said motion to the slide, a sleeve mounted on the shaft, rotatory therewith, movable longitudinally thereon, and connected with said lever-arms, and a non-rotatory yoke for actuating said 85 sleeve, substantially as and for the purposes described.

5. The combination, with a rotatory shaft, of a slide capable of rotation therewith and movable towards and away from its axis, and provided with a circular surface for transmitting motion, lever-arms connecting with said slide and with said shaft and capable of imparting the said motion to the slide, a sleeve mounted on the shaft, rotatory therewith, 95 movable longitudinally thereon, and connected with said lever-arms, a collar loosely mounted on said sleeve so that the latter may rotate therein, and a non-rotatory yoke connected with said collar and capable of moving the 100 collar and the sleeve, substantially as and for the purposes described.

6. The combination, with a rotatory shaft, of a slide capable of rotation therewith and movable toward and away from its axis, and provided with a circular surface for transmitting motion, lever-arms connecting with said slide and with said shaft, and capable of imparting the said motion to the slide, a non-rotatory yoke for actuating said levers, and a 110 screw-shaft gearing into said yoke and capable of moving the same by rotation of the shaft, substantially as and for the purposes described.

In testimony whereof I have hereunto set 120 my hand this 5th day of January, A. D. 1885.

HERMANN SCHULZE-BERGE.
